UNITED STATES PATENT OFFICE.

FRANK J. GIBBS, OF TYRONE, PENNSYLVANIA.

TROLLEY.

No. 815,283.

Specification of Letters Patent.

Patented March 13, 1906.

Application filed January 20, 1906. Serial No. 241,860.

To all whom it may concern:

Be it known that I, FRANK J. GIBBS, a citizen of the United States, residing at Tyrone, in the county of Blair and State of Pennsylvania, have invented a new and useful Trolley, of which the following is a specification.

This invention relates to improvements in trolleys for use in securing electrical connections with overhead feed-wires.

10 One of the objects of the invention is to provide a novel structure which will have spaced bearings upon the wire, will accommodate itself to the curves thereof and kinks therein, and will therefore more securely 15 maintain a proper engagement with such wire.

A further object is to provide a structure which will practically be suspended from the pole bracket-arms, so that it will maintain a 20 proper position even when disengaged from the wire, thereby obviating the objection of top-heaviness and permitting the convenient and ready replacement or engagement of the trolley with the wire.

25 An embodiment of the invention that is at present considered preferable is illustrated in the accompanying drawings, wherein—

Figure 1 is a side elevation of such embodiment. Fig. 2 is a top plan view of the 30 same. Fig. 3 is a longitudinal sectional view. Fig. 4 is an end elevation of the front trolley-wheel and guide-rollers therefor, a portion of said wheel being shown in section. Fig. 5 is a rear elevation of the gear-wheel and the 35 guide-arms coacting therewith. Fig. 6 is a cross-sectional view taken on the line 6 6 of Fig. 2. Fig. 7 is a detail bottom perspective view of the carrier-bracket and the positioning-spring mounted thereon, and Fig. 8 is a 40 detail perspective view of the body of the pivot member.

Similar reference-numerals designate corresponding parts in all the figures of the drawings.

45 In the embodiment illustrated a portion of a pole 9 is employed, which may be of any well-known or desired construction and carries at its upper end spaced bracket-arms 10, the upper terminals of which are provided 50 with eyes 11. Said upper terminals are connected by a pivot member consisting of a body 12, located between the arms and connected thereto by headed journal-pins 13, threaded into the ends of the body and rotatably passing through the eyes 11. A 55 head member 14 is also located between the

bracket-arms 10 and consists of a top plate 15, located over the pivot-member body, said plate having depending side walls 16, provided with slots 17, through which the journal-pins 13 pass, the end walls 18 of the slots being adapted to abut against the journal-pins and constituting stop-shoulders, as is hereinafter described. The head 14 is provided with a depending substantially upright 65 pivot 19, which may be integral therewith and preferably is so constructed in order that it may turn with the head. This pivot 19 passes downwardly through an opening 20, formed in the body 12 of the pivot member, 70 the lower end of the pivot being reduced in diameter and constituting a stem 21, which is threaded and has a longitudinal keyway 22. By this pivotal connection it will be apparent that the head 14 can swing in a substantially horizontal direction upon the pivot member, this swinging movement being limited by the length of the slots 17, or, in other words, by the engagement of the end walls 75 of the shoulders 18 with the journal-pins 13. Furthermore, as the pivot member can turn 80 on a horizontal axis the said head is also capable of an upright swinging movement.

In order to reduce friction between the pivot member and head, roller-bearings in 85 the form of balls 23 are interposed between said head and the body 12, being preferably located in raceways or grooves 24, formed in the upper side of said body 12 contiguous to the ends of the same and also in a circle about 90 the pivot.

In order to prevent the head becoming detached from the pivot member, a nut 25 is threaded upon the stem 21 of the pivot, and for the purpose of maintaining the head in a 95 predetermined position with respect to the pivot member a positioning-spring is employed. This positioning-spring is a leaf-spring 26, secured between its ends to the curved flange 27 of a carrier-bracket 28, 100 mounted upon the stem 21 below the nut 25 and having a key 29, that engages in the keyway 22, said brackets being thus held against relative rotation with respect to the pivot by said key and being maintained against displacement by a nut 30, threaded on the stem and bearing against the bracket. The leaf-spring 26 is fastened to the flange by suitable rivets 31 or other fasteners, which pass through said flange 27, through the spring 26, 105 and through a guard-plate 32, located outside said plate. The terminal portions of

the spring slidably engage in guideways 33, formed on the pivot-member body 12 by means of depending offset lugs 34, spaced from and carried by the body member, all of which is shown in Fig. 2 of the drawings.

The head 14 carries oppositely-extending ears 35, located in advance and in rear of the pivot member, these ears terminating in up-standing hook portions 36, that receive axles 37, on which are journaled trolley-wheels 38, preferably ball-bearing, as indicated in dotted lines in Fig. 4 at 39. It is to be observed that the axles 37 are located lower than the axis of movement of the pivot member and that the front axle is disposed closer to said pivot member than the rear axle. This disposition is important for the reasons herein-after set forth. Contact-plates 37^a, secured to certain of the ears 35, have offset terminals provided with openings that receive the reduced ends 38^a of the wheel-hubs and bear against shoulders 39^a thus formed on said hubs. Secured to the front ears 35 of the head, by means of the front axle 37, are up-standing brackets 40, having spaced inner and outer legs 41, to and between which are journaled cone guide-rollers 42, located on opposite sides of the front wheel 38, with their inner peripheral margins disposed directly adjacent thereto. Secured in like manner to the rear ears 35 of the head, by means of the rear axle 37, are rearwardly and upwardly extending guide-arms 43, the upper terminal portions 44 of which diverge, while the intermediate portions of said arms are located directly adjacent to the peripheral edges of the wheel, as illustrated in Fig. 5. An opening 45 is formed in one of the depending side walls 16 of the head, and in this opening is secured the usual trolley-rope 46.

It will be observed that when the trolley-wheels 38 are upon a feed-wire they can continue in contact with the same without regard to the curves thereof or the kinks therein, and even should one of the wheels break such contact for an instant the other will remain in engagement, and thus sparking to a very considerable degree is avoided. The wheels can turn to follow the curvatures of the wire, for the head carrying said wheels can turn horizontally on its vertical pivotal connection with the pivot member and can also swing vertically, because of the pivotal connections of said member with the bracket-arms of the pole. The positioning-spring, however, normally maintains the head in a predetermined relation with respect to the pivot member, as will be apparent, and thus if the wheels are removed from the wire this positioning-spring will hold the head in such position. Furthermore, when the trolley is disengaged from the wire, being practically suspended from the hanger-arms, it will not be top-heavy. This, it is thought, will be apparent when it is considered that the axles

of the wheels are located below the pivot-axis of the pivot member and said member is arranged as high as is practicable. The rear end of the trolley, moreover, overbalances the front end, so that said rear end will drop to the lower position. In placing the trolley upon a wire strain is of course put upon the rope 46. This will cause the head to swing in an upright direction, raising the rear wheel above the front wheel and moving the guide-arms 43 to a substantially upright position, so that the rear wheel can be conveniently engaged with the wire. Upon releasing the strain upon the rope 46 the front wheel will move upwardly and the wire, guided by the cone-rollers, will engage the same. When both wheels are upon the wire, the rear guides extending rearwardly are substantially out of the way of cross-supports and similar devices. The structure, therefore, is so formed that it may be conveniently and readily placed against the wire.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a trolley, the combination with a supporting-pole having upstanding bracket-arms, of a head located between the bracket-arms, a transverse substantially horizontal pivot member connecting the head between its ends and the arms, trolley-wheels located in advance and in rear of the pivot member, and axles for the wheels carried by the head, said axles being disposed lower than the pivot member and the front axle being arranged nearer the axis of said pivot member than the rear axle, whereby the rear end of said head overbalances the front end.

2. In a trolley, the combination with a support, of a pivot member pivotally mounted on the support, and a head movably mounted on the pivot member and swinging therewith in one direction, said head having a movement on the pivot member in another direction, and said pivot member having a portion thereof located in the path of movement of the head for limiting the swinging movement of said head upon and with respect to the pivot member.

3. In a trolley, the combination with a support, of a pivot member movably mounted on the support, and a swinging head pivotally supported on the pivot member, said pivot member having a portion constituting a stop to limit the swinging movement of the

head with respect to said pivot member, said head swinging into and out of engagement with said portion.

4. In a trolley, the combination with a support, of a pivot member pivotally mounted on the support, a swinging head, and a pivot connecting the head and pivot member and extending transversely of the latter, said head being arranged to engage the pivot member upon its swinging movement on the pivot and being thereby limited in said swinging movement.

5. In a trolley, the combination with a support, of a pivot member pivotally mounted on the support, a swinging head, and a pivot connecting the head and pivot member and extending transversely of the latter, said head having stop-shoulders arranged to abut against the pivot member.

6. In a trolley, the combination with a support, of a pivot member pivotally mounted in the support, a swinging head, and a pivot connecting the head and pivot member and extending transversely of the latter, said head having a depending wall provided with a slot through which the pivot member extends.

7. In a trolley, the combination with a pole having bracket-arms, of a member connecting the arms, a head located over the member and having depending side walls provided with slots through which the member passes, a trolley-wheel carried by the head, and a pivotal connection between the head and member.

8. In a trolley, the combination with a pole having bracket-arms, of a pivot member connecting and journaled upon the bracket-arms, a head comprising a casing located over the pivot member, a depending pivot for the head passing through the pivot member, said head having side walls provided with slots through which the pivot member passes, and trolley-wheels journaled on the head in advance and in rear of the pivot member.

9. In a trolley, the combination with a pole having bracket-arms, of a pivot member connecting the arms, a head extending over and on opposite sides of the pivot member between the arms, an upright pivot connecting the head and member, wheels carried by the head on opposite sides of the member, a series of balls interposed between the head and pivot member and disposed directly about the pivot, and other balls interposed between the pivot member and head directly adjacent to the connections of said pivot member with the bracket-arms.

10. In a trolley, the combination with a pole having upstanding arms provided with eyes, of a pivot member comprising a body portion, journal-pins engaging said body portion and passing through the eyes of the bracket-arms, a head extending over the pivot member and having oppositely-extend-

ing ears, wheels journaled to and between the ears, depending walls constituting parts of said head and having slots through which the journal-pins pass, and roller-bearings interposed between the head and body of the pivot member.

11. In a trolley, the combination with a pole having bracket-arms, of a pivot device connecting the arms, a head, a pivot connecting said device and head, a wheel carried by the head, and a positioning-spring carried by the pivot, extending longitudinally of the axis of said pivot device, and transversely of the head, said spring having an interlocked engagement with the device for maintaining the head in a predetermined position.

12. In a trolley, the combination with a support, of a pivot member pivotally carried thereby and having a guideway, a head pivoted on the member and movable therewith and with respect thereto, a wheel carried by the head, and a positioning-spring movable with the head and slidably in the guideway upon the movement of said head with respect to the pivot member.

13. In a trolley, the combination with a support, of a pivot member pivotally mounted thereon transversely of the support and having an offset lug forming a guideway, a head mounted on the pivot member, a substantially upright pivot connecting the member and head and turning in the pivot member, and a leaf-spring secured to the pivot and swinging upon the movement thereof, said spring having a free portion slidable in the guideway formed by the lug.

14. In a trolley, the combination with a pole having spaced bracket-arms, of a pivot member journaled on the bracket-arms, a head carrying a trolley-wheel, a substantially upright pivot carried by the head and journaled in an intermediate portion of the pivot member, offset lugs carried by and spaced from the pivot member on opposite sides of the pivot, and a leaf-spring secured between its ends to the pivot and having its terminal portions slidably bearing against the lugs.

15. In a trolley, the combination with a support, of a member mounted on the support transversely thereof, a head carried by the member and having a trolley-wheel, said member extending transversely of the head, a pivot carried by the head and passing through the member, a carrier-bracket secured to the pivot and turning therewith, and a leaf-spring secured between its ends to the carrier-bracket and having its terminal portions slidably interlocked with the member.

16. In a trolley, the combination with a pole having spaced bracket-arms, of a pivot member connecting the arms, a head mounted on the pivot member and having a substantially upright swinging movement, trolley-wheels located in front of and behind the

5 pivot member, guide-rollers carried by the front portion of the head and located on opposite sides of the front wheel, and rearwardly-extending guide-arms carried by the rear end of the head and having divergently-disposed terminals located on opposite sides of the rear wheel.

17. In a trolley, the combination with a support, of an axle secured thereto a trolley journalled on the axle and having a hub provided with a reduced rotating portion forming a shoulder, and a contact-plate secured to the support and having an opening that receives the reduced portion of the hub said plate bearing against the shoulder and said reduced portion of the hub rotating in the plate.

18. In a trolley, the combination with a pole, of a head having a pivotal connection between its ends with the pole, wheels journalled upon the head and on opposite sides of said pivotal connection, the front wheel being disposed closer to the said connection than the rear wheel, rearwardly-extending

25 guide devices carried by the rear portion of the head on opposite sides of the wheel, and means connected to the head between its ends for raising the rear portion of the head and bringing the guide devices substantially to upright position.

19. In a trolley, the combination with a support, of a member mounted on the support, a head carried by the member and having a trolley-wheel, a pivot carried by the head and passing through the member, a carrier-bracket mounted on the pivot, said bracket and pivot having an interlocking 35 key and keyway connection, a flange forming a part of said bracket, and a spring secured to the flange and engaged with the said member.

In testimony that I claim the foregoing as my own I have hereto affixed my signature in the presence of two witnesses.

FRANK J. GIBBS.
